Claims priority, application Germany July 29, 1959
14 Claims. (Cl. 62—9)

This invention is concerned with the provision of a process of and an apparatus for producing refrigeration through high-pressure gas of above-critical pressure with cooling through work-performing expansion for meeting the requirements in the liquefaction—or in the separation into its components—of the gas. The expressions "critical temperature" and "critical pressure" as used herein are intended to have the meanings given for them in "Handbook of Chemistry and Physics," 42nd ed., 1960/61, page 3082.

It is known, according to the process of Heylandt, that high-pressure gases of, for example, 200 atmospheres gauge pressure can be cooled by work-performing expansion, the cooling thereby obtained being transmitted—after an interposed separation of the gas in some cases—to another part of the high-pressure gas and the latter liquefied by throttling. In this process, a very large pressure drop takes place in the expansion machine, for which reason piston machines must generally be employed. During the work-performing expansion the gas is cooled to such an extent that its temperature lies only a little above the liquefaction limit.

An object of the present invention is to restrict the work-performing expansion to a partial pressure drop in the below-critical pressure range, but to carry out the process at relatively highly elevated temperature, preferably in the above-critical temperature range. The first criterion makes it possible to have the work-performing expansion for large gas volume take place with particularly high thermal efficiency: the latter criterion utilizes the fact that the refrigerating capacity, for equal pressure drop, is the greater the higher is the mean working temperature of the expansion.

In the predominantly above-critical pressure range the invention utilizes only the Joule-Thomson cooling effect for the refrigeration; in the range of below-critical pressures, however, there is additionally utilized the very good refrigerating capacity of a work-performing expansion at high mean working temperature. The cold produced at high working temperature through work-performing expansion is, then, transformed to the much lower required temperature through the total high-pressure air, and therefore, not only through the non-work-performing expanding part according to the principle of the vaporization refrigeration machine.

Accordingly, the invention concerns the production of refrigeration by high-pressure gas of above-critical pressure with cooling through work-performing expansion for the coverage of the cooling losses in the liquefaction of the gas, or in the separation of the gas, for obtaining liquefied gases and/or, in a given case, for obtaining liquid gas separation products—in particular, of air separation products—and is thereby characterized in that the high-pressure gas of above-critical pressure of preferably 100 to 300 kg./cm.², cooled by means of the expanded gas or expanded gas separation products, is throttled to below-critical pressure of preferably 10 to 30 kg./cm.², separated from the liquefied part in the heat-exchange with the high-pressure gas or considerably warmed with a part of the same, cooled through work-performing expansion and then, in some cases with an interposed gas separation in

2

the heat exchange with the high-pressure gas or a part of the same, again heated to room temperature.

This has the advantage first of all that in the work-performing expansion at small pressure drop and high mean working temperature a higher thermal efficiency can be attained than at higher pressure drop. The greater expansion volume as compared with the expansion with large pressure drop makes it possible to build large machine units since turbines—which do not permit any lubricant to enter the expanded gas—are less susceptible to disturbances, and entail smaller installation costs, than do reciprocating expansion machines.

In spite of the decreased pressure drop the work-performing expansion, on account of the higher mean working temperature, does not give a smaller cooling effect than does the high-pressure expansion over the entire high-pressure drop. At the same time, the simpler constructions designed as turbines are accompanied by an installation and smaller space requirement for the expansion machines designed as turbines are accompanied by an at least equal refrigeration capacity of the high-pressure expansion.

In applying the process according to the invention for a high-pressure cycle incorporated with a gas separation installation the expansion turbine, in a special design form with closed cycle, is operated with the total cycle quantity, in comparison with the familiar processes with high pressure expansion machines which have available only about 60 percent of the gas for the work-performing expansion.

The refrigeration is in this case produced through indirect heat-exchange, transmitted to a special dry-condensed cycle gas, and through the latter supplied to the separation apparatus so that not even traces of oil from the compressors for compressing the high-pressure cycle gas can reach the separation apparatus.

In the process according to the invention high-pressure gas of above-critical pressure, preferably between 100 to 300 kg./cm.², is supplied to a first heat-exchanger in which the gas is cooled through heat-exchange with cold gas coming from the expansion turbine. The high-pressure gas is then divided into two partial streams each of which is further cooled by an additional heat-exchanger. One of the streams is cooled by the gas coming from the expansion turbine, the other by the gas going to the turbine. After traversing these heat-exchangers the two partial gas streams, either separated or combined, pass through a heat-exchanger in which they are further cooled by the gas flowing back from the expansion vessel to the turbine. The two separated partial streams are then expanded into an expansion vessel to below critical pressure, preferably between 10 and 30 kg./cm.², whereby a part of the gas is liquefied. The liquefied part can be removed while the remaining gaseous part flows back through the heat-exchanger connected ahead of the expansion turbine, is thereby heated, and is then expanded in the expansion turbine. After expansion, the gas flows back through the heat-exchanger and is heated by the arriving high-pressure gas. The high-pressure gas, already compressed and dry, is supplied from the outside to the first heat-exchanger of the installation. It is of advantage to employ a gas cycle where the back flowing gas is compressed by a compressor and where the quantity drawn off as liquid, through the supply of fresh gas before, during or after the compression, in the warm portion, is, after the work-performing expansion, replaced by gas coming from the low-temperature part of a gas separation apparatus in the cold part of the cycle.

If the process described thus far is used in connection with a familiar gas separation apparatus—for example, one which uses regenerators for the heat-exchange—the

expansion vessel in which the liquefied high-pressure gas collects can communicate with the separation column. By transferring an equivalent gas quantity from the low-temperature part of the gas separation apparatus under separation pressure back to the cold part after the work-performing expansion, the pressure behind the expansion machine will be held constant at the pressure of the separation column. From the pressure-column a two-column rectification installation, for example, the low boiling gaseous end product can be removed and with it the cycle operated or replenished.

The liquid expanded in the separation apparatus can be undercooled by the gas supplementing the cycle or by the gas separation product before this supplementing gas is itself supplied to the cycle. It is also possible to heat the supplementing gas for the cycle in the indirect heat-exchanger with the gas to be separated, in particular, through pipe coils which are embedded in the main heat-exchangers of the gas separation apparatus, preferably in the storage mass of regenerators, and to supply it to the cycle in the heated state before the compression.

The gas liquefied in the expansion vessel can also be again vaporized through indirect heat-exchange with another gas. The total cycle gas is then available for the work-performing expansion. Thereby this other gas can be liquefied. In this case the total expanded high-pressure gas of the installation can be repeatedly compressed and expanded in the closed cycle.

This second gas can be compressed to a pressure at which it is itself liquefied through evaporation of the liquefied part of the throttled high-pressure gas. In this process the second gas to be liquefied can be precooled (entirely, or in part) in the heat-exchange with the cycle gas to be heated or with a part of it.

It is, furthermore, possible to take high-boiling point gas from a gas separation installation and to compress it, preferably dry and free of oil, to a pressure such that it vaporizes the liquefied cycle gas in the indirect heat-exchange and is itself liquefied in the process. The liquefied gas is then expanded into the separation apparatus. The expansion pressure of the work-performing expansion of the cycle can thereby be held at constant pressure through communication with suitable parts of the separation apparatus under constant pressure.

The liquefied high-boiling point gas in indirect heat-exchange with the liquefied cycle gas to be vaporized can, before its compression, be totally or partially heated through indirect heat-exchange by pipe coils inserted in the main heat-exchangers of the gas separation apparatus—in the case of regenerators, in the storage mass—while a part of the high-boiling point gas can be heated in indirect heat-exchange with itself before the compression. If occasion arises, the compression of the high-boiling point gas can take place in common with the compression of the high-boiling point gas intended for consumption, preferably dry and free of oil.

To maintain the temperature equilibrium in the regenerators, a portion of the work-performing expanded cold cycle gas, that is regulateable by hand or automatically, can be conducted through the pipe coils in the regenerators and again be supplied to the warm part of the cycle. The gas quantity to be warmed in the pipe coils in the regenerators can also be cooled to the separation temperature by the expansion temperature of the work-performing expansion before the heating in the pipe coils or, without preliminary further cooling, only be conducted in the warmer part of pipe coils in the regenerators.

In the application of the process in air separation installations the expansion machines are preferably operated with air or nitrogen, preferably between 20 to 35 atmospheres and about 5 atmospheres, and for the possible evaporation of the liquefied cycle gas oxygen preferably is used which desirably is compressed to 15 to 30

atmospheres. The process can also be applied to other gas mixtures than air.

The invention will be described in further detail and with reference to the accompanying drawings, in which the four figures show schematically and as examples, apparatus for carrying out the process. The same parts are indicated by the same figures.

FIG. 1 shows an installation in which the gas is compressed in the compressor to above-critical pressure and is supplied to the first heat-exchanger 2 through the pipe 11. In the heat-exchanger the gas is cooled by counter-flowing cold gas. The gas stream is then divided at 13, one part passing through the heat-exchanger 4 and there being cooled by the cold gas coming from the turbine 3 over pipe 14, while the other part of the gas stream is cooled in the heat-exchanger 5 by the gas flowing to the turbine. The two gas streams, separated in the pipes 16 and 17, are then led to a heat-exchanger 6 where they are further cooled through the non-liquefied portion of the gas flowing back through the pipe 19. The separated streams are then expanded through the valves 7 and 8 in the expansion vessel 9 to below-critical pressure. Thereby a part of the gas is liquefied and collects in vessel 9, while the non-liquefied part is conducted to the expansion turbine through pipe 19, heat-exchanger 6, pipe 18, heat-exchanger 5 and pipe 15. A pipe 14 conducts the expanded gas to heat-exchanger 4 from which it goes to the heat-exchanger 2 and from there, by way of pipe 12, again to the compressor 1. The gas condensed as liquid can be replaced by dry low-pressure gas through pipe 22 and valve 23, or by dry high-pressure gas through a pipe 21 shown in dotted line. It is also possible to omit the compressor entirely and to conduct the high-pressure gas by way of pipe 21 from the outside of the installation. The liquid accumulated in the expansion vessel 9 can be drawn off by the valve 10 through pipe 20.

FIG. 2 shows an installation in which the condensed high-pressure gas is vaporized through indirect heat-exchange with a condensing auxiliary gas. This gas is supplied to the apparatus through the pipe 24. A part flows through pipe 26 and the heat-exchanger 29 into the pipe coils 31 in the expansion vessel 9, while another part of the supplied gas is supplied by way of pipe 25 to the heat-exchanger 27, then to heat-exchanger 28 and by way of pipe 30 likewise to the pipe coils 31. The gas is then expanded through a valve 32 into a vessel 34. Here the condensed gas is accumulated and can be drained off through a valve 33. The non-condensed part flows through pipe 35 to the heat-exchanger 29 and leaves the apparatus at 36.

FIG. 3 shows an installation in which the process according to the invention can be applied to the production of refrigeration for a gas separating installation. Of the low temperature gas separation installation only a two-stage rectifying column 39, 40 is schematically represented in which all parts non-essential for the process according to the invention have been omitted; namely, the pipes to and from the column as well as the pipes and valves for the wash liquids are not represented. There are also omitted the principal heat-exchangers, for example, regenerators, for the entering or leaving gas. As cycle gas, low-boiling point gas is taken in the gaseous form from pressure column 39 through a pipe 41 and supplied to the heat-exchanger 4 by way of an undercooled counterflow heat-exchanger 47. From heat-exchanger 4 it passes through heat-exchanger 2 and pipe 12 to the compressor 1. In the manner already described, a part of the gas is liquefied by expansion into the expansion vessel 9. The liquid in pipe 37 is conducted through the undercooling heat-exchanger 47, expanded through the nozzle 38 and again supplied to the lower column of the two-column rectifier 39.

FIG. 4 shows an installation in which high-boiling point gas is liquefied in a cycle separated from the ex-

pansion cycle. The high-boiling point gas is taken from the column 40 through pipe 42 and conducted through the pipe coils 49, which are inserted in regenerators not here indicated, to the compressor 43. Here the gas is compressed to the pressure at which it condenses in heat-exchange with the liquid to be vaporized in the expansion vessel. It is conducted to through pipe 45 to a heat-exchanger 27 and then to a heat-exchanger 28 before it is liquefied in pipe coils 31. It is then conducted through pipe 46 to the heat-exchanger 47 and, with the aid of valve 48, expanded into the upper column 40. Compressed, high-boiling point gas can be taken from the installation through the valve 44. Moreover, for suitable refrigeration capacity, liquid products can be taken from the gas separation installation, for example, liquid high-boiling point material through the pipe 50.

I claim:

1. In a process for the production of cold by throttling and work-performing expansion of a gas, the method which comprises cooling a gas which has been compressed (1) to above critical pressure at ambient temperature in a first cooling stage (2), dividing said compressed and cooled gas (13) into a first stream (16) and a second stream (17), cooling said first and said second streams in a second cooling stage (4, 5) and in a following third cooling stage (6), throttling said first and said second streams separately (7, 8) to below-critical pressure thereby liquefying them at least partially, separating a gaseous part from a liquid part (9), withdrawing the gaseous part (19), heating it by heat-exchange with the first and the second streams in the third cooling stage (6), heating it further by heat-exchange with the second stream in the second cooling stage (5), expanding it by work-performing expansion (3), heating said expanded gas by heat-exchange with the first stream in the second cooling stage (4), and then heating it in said first cooling stage (2) by heat-exchange in the compressed gas to ambient temperature.

2. Process according to claim 1, in which the compressed gas after expansion and warming to ambient temperature is compressed and expanded again in a cycle.

3. Process as claimed in claim 1, in which the separated liquefied part from the process is withdrawn and replaced by cold dry gas before said first cooling stage.

4. Process according to claim 1, in which the separated liquid part is withdrawn from the process and is replaced by compressed gas of ambient temperature before said first cooling stage.

5. Process according to claim 1, in which the separated liquid part is evaporated by heat-exchange with a condensing gas (31) and the gas being formed by said evaporation is processed together (19) with the gaseous part remaining after throttling the compressed cooled gas.

6. In a process for the production of cold in a low temperature gas separation plant comprising a rectifying device, the method which comprises withdrawing a part of a separation product in gaseous form from the rectifying device, warming it to ambient temperature in countercurrent with a warm gas to be cooled, compressing it to above-critical pressure, cooling it by heat-exchange with the gaseous separation product withdrawn from the rectifying device, throttling it to a below-critical pressure thereby liquefying part of it, separating gaseous part from liquid part, heating the gaseous part by heat-exchange with the compressed separation product, expanding it by work-performing expansion and heating it together with the separation product withdrawn from the rectifying device, and feeding the liquid part, obtained by throttling, into the rectifying device.

7. In a process for the production of cold in a low temperature gas separation plant comprising a rectifying device, the method which comprises withdrawing a part of the low boiling component in gaseous form (41) from the rectifying device (39) warming it by heat-exchange in a fourth cooling stage (47) heating it further by heat-

exchange in a second (4) and in a first (2) cooling stage, compressing it to above-critical pressure (1) and cooling it in countercurrent with itself in said first cooling stage (2), dividing the compressed and cooled gas (13) into a first stream (16) and a second stream (17), cooling said first and said second streams in the second cooling stage (4, 5) and in a following third cooling stage (6), throttling said first and said second streams separately (7, 8) to below critical pressure thereby liquefying them at least partially, separating a gaseous part from a liquid part in a separator (9), withdrawing the gaseous part (19), heating it by heat-exchange with the first and the second streams in the third cooling stage (6), heating it further by heat-exchange with the second stream in the second cooling stage (5), expanding it by work-performing expansion (3), heating the expanded gas by heat-exchange with the first stream in the second cooling stage (4) together with the gas withdrawn from the rectifying device (39) in the second (4) and the first (2) cooling stage to ambient temperature, withdrawing the liquid part (37) from said separator (9) cooling it in heat-exchange in said fourth cooling stage (47), throttling it (38) and feeding it into said rectifying device (39).

8. Process as claimed in claim 7, in which the gas to be separated is air, and in which the low boiling component withdrawn from the rectifying device is nitrogen and this nitrogen is compressed to an above-critical pressure of from about 100 to about 300 kg./cm.² and throttled to a below-critical pressure of from about 10 to about 30 kg./cm.².

9. In a process for the production of cold in a low temperature gas separation plant which comprises a refrigerating cycle according to claim 5, and which comprises further withdrawing part of a gas separation product from the rectifying device, heating it to ambient temperature (49), compressing (43) it, withdrawing (44) part of it from the gas separation plant and cooling (27, 28, 31) the remaining part by heat-exchange with gas of the refrigerating cycle, condensing it by heat-exchange with evaporating liquid obtained by throttling the compressed gas of the refrigerating cycle, and feeding the condensed gas into the rectifying device.

10. In a process for the production of cold in low temperature gas separation plant comprising a rectifying device the process which comprises withdrawing part of the high boiling component from the rectifying device (4) in gaseous form, warming it to ambient temperature (49), compressing it (43), cooling it by heat-exchange (27, 28) with gas of a refrigerating cycle, condensing it by heat-exchange (31) with a liquid contained in a separator (9) and feeding it (46) back into the rectifying device (40), withdrawing (41) part of the low boiling from the rectifying device (39) component for compensating losses of the gas of the refrigerating cycle, warming it in a second cooling stage (4, 5) heating it further in a first cooling stage (2) in countercurrent with itself, compressing it to above-critical pressure (1), cooling it in said first cooling stage (2), dividing the compressed and cooled gas (13) in a first stream (16) and a second stream (17), cooling said first and said second stream in the second cooling stage (4, 5) and in a following third cooling stage (6), throttling said first and said second stream separately (7, 8) to below-critical pressure thereby liquefying them at least partially, separating a gaseous part from a liquid part in said separator (9) withdrawing the gaseous part (19), heating it by heat-exchange with the first and the second stream in the third cooling stage (6), heating it further by heat-exchange (28) with the high boiling component to be liquefied then by heat-exchange with the second stream in the second cooling stage (5), expanding it by work-performing expansion (3), heating the expanded gas by heat-exchange with the first stream in the second cooling stage (4) together with the gas withdrawn from rectifying de-

vice (41) in the second (4) and the first (2) cooling stage to ambient temperature.

11. Apparatus for production of cold in a gas liquefaction plant or in a plant for gas separation by work-performing expansion, in which the output of a compressor is connected to the warm end of one flow path of a first heat-exchanger, the cold end of which latter is connected to one flow path of a second heat-exchanger and one flow path of a third heat-exchanger, the cold ends of the second and third heat-exchangers are connected to the warm ends of two flow paths in a fourth heat-exchanger, and the cold ends of said two flow paths are connected by valve-equipped connections with the medium part of a vessel; connecting means from the head of said vessel to the cold end of a third flow path of the 15 fourth heat-exchanger, connecting means from the warm end of said fourth heat-exchanger to the cold end of a second flow path of the third heat-exchanger, means connecting the warm end of said second flow path of said third heat-exchanger to the input of an expansion machine, means connecting the output of said expansion machine to the cold end of the second flow path of said second heat-exchanger, and means connecting the warm end of said second heat-exchanger to the cold end of the 20 first heat-exchanger, and means connecting the warm end of the first heat-exchanger to the input of said compressor.

10
15
20

12. Apparatus as defined in claim 11, in which there are provided heat-exchanging means, in particular pipe coils, in the lower part of said vessel for liquefying a gas in said heat-exchanging means.

13. Apparatus as defined in claim 11, in which the bottom of said vessel is connected by heat-exchanging and expansion means with a rectifying column.

14. Apparatus as defined in claim 13, in which the warm end of one flow path of said heat-exchanging means is connected with the rectifying column, and the cold end of which is connected with the cold end of said second flow path of said second heat-exchanger.
